POWER SHOVEL MECHANISM

Edmund Joseph Kane, Chicago, Ill.

Application May 10, 1929, Serial No. 361,873

5 Claims. (Cl. 214—135)

This invention relates to mechanism for power shovels and cranes, and particularly to novel means for actuating the dipper sticks of power shovels, and to means for adapting the machine for use as a shovel or crane.

Among other objects, the present invention is intended to provide a novel construction and arrangement for imparting an efficient crowding and retracting motion to the dipper stick and dipper.

Another object of the invention is to provide a novel construction and arrangement whereby the machine to which the invention is applied may be readily adapted for use as a crane or power shovel.

A further object of the invention is to improve machines of the character disclosed in sundry details hereinafter described and particularly pointed out in the appended claims.

One embodiment of the invention is shown for illustrative purposes in the accompanying drawings, in which

Fig. 1 is a side elevation of a machine equipped for use as a power shovel, and illustrating the application of my invention thereto.

Fig. 2 is an enlarged side elevation of a portion of Fig. 1.

Fig. 3 is a sectional view taken substantially as indicated by the line 3—3 of Fig. 2 and showing portions of some of the parts in elevation.

Fig. 4 is an elevational view taken substantially as indicated by the line 4—4 of Fig. 3.

Fig. 5 is a fragmentary plan view of a portion of the boom shown in Fig. 1, and illustrating the driving connection for rotating the shipper shaft and reciprocating the dipper stick.

Fig. 6 is an elevational view, partly in section, of a portion of Fig. 3 illustrating means for adapting the machine for use as a crane.

Fig. 7 is a side elevation of the drum lagging shown in Fig. 6 and illustrating the manner of securing the lagging to the drum shaft sleeve.

Fig. 8 is a sectional elevation through the drum lagging taken substantially as indicated by the line 8—8 of Fig. 7.

The illustrative embodiment of the present invention is shown applied to a machine equipped for use as a power shovel which comprises a pivoted swing body 10, suitably mounted for transportation on endless track laying devices 11, and having a suitable power unit mounted thereon, such, for example, as an internal combustion engine, designated by the numeral 12, from which power is transmitted by means of a chain 13 to a main power shaft 14, thence through suitable

connections to the track laying devices 11, and to the large annular ring gear 15 for swinging the body 10 about its pivot.

Pivotedly mounted adjacent the forward edge of the swing body 10 on hollow pivot pins or trunnions 16 formed on brackets 16a is a boom 17 on which is rotatably mounted a shipper shaft 18 having secured thereto, at opposite sides of the boom a pair of pinions 19 adapted to co-operate with racks 20 secured to the portions 21 of a split or bifurcated dipper stick, on the outer end of which is suitably mounted a dipper 22, the connection between the pinions 19 and racks 20 being such that as the shipper shaft is rotated in one direction or another, the portions 21 of the dipper stick will be reciprocated longitudinally and the dipper moved outwardly or inwardly with respect to the boom 17 according to the direction of rotation of the shipper shaft. A cable 23, having suitable connections with the power mechanism, may be employed for swinging the dipper and sticks about the shipper shaft, and the cable 24, also having suitable connections with the driving means, may be employed for swinging the boom about its pivotal connection with the brackets 16a, but inasmuch as these cables and the pivotal movement of the dipper and boom form no part of the present invention, their particular connection with the driving mechanism has been omitted from the drawings to facilitate the showing of features embodying the present invention.

For driving the shipper shaft in one direction, namely, in a direction to retract the stick 21 and move the dipper 22 toward the boom, a drum shaft 25 is rotatably mounted in bearings 26, suitably positioned on the swing body 10, and secured to the drum shaft 25, by means of a key 27, is a large gear 28 adapted to mesh with a small pinion 29 secured to the main power shaft 14 by which the drum shaft 25 is continuously rotated when the engine 12 is in operation.

Rotatably mounted on the drum shaft 25 is a driving member or sleeve 30 having a sprocket 31 formed thereon and a removable member or sprocket 32 secured thereto, thus forming, in effect, a double sprocket rotatably mounted on the drum shaft 25.

Rotatably mounted in the trunnions 16 and concentrically with the pivotal connection of the boom 17 is a boom pivot shaft 33 to which is secured, adjacent its central portion, sprockets 34 and 35 thus making a power transmitting or jack shaft of said axial boom pivot shaft, the sprocket 34 being connected by means of a chain

36 with the sprocket 31 formed on the sleeve or driving member 30, and the sprocket 35 being connected by means of a chain 37 with a sprocket 38 secured to the shipper shaft 18 adjacent its central portion.

For connecting the driving member or sleeve 30 to the drum shaft 25, the gear 28 is provided with a plurality of pivotally mounted bell crank levers 39, to the short arms of which are operatively connected segmental clutch bands 40 adapted to co-operate with a clutch drum 41 formed on the driving member or sleeve 30, while to the long arms of the bell crank levers 39 are connected anti-friction rollers 42 adapted to enter suitably positioned apertures 43 formed in the hub portion of the gear 28 in a manner to be engaged by a wedge 44 slidably mounted in the end of the drum shaft 25, the moving of the wedge 44 inwardly acting to move the anti-friction rollers 42 on the long arms of the bell crank levers outwardly in a manner to cause the bands 40 to grip the drum 41 and establish an operative driving connection between the drum shaft 25 and the driving member or sleeve 30.

For moving the wedge 44 inwardly and outwardly of the drum shaft 25 in a manner to connect and disconnect the said shaft and driving member 30, a manually operated hand lever 45 is secured to a shaft 46, rotatably mounted on the frame or swing body 10, and secured to the shaft 46 is an arm 47 having its free end connected to the lower end of a link 48, the upper end of which is secured to the free end of an arm 49 connected with a short shaft 50 rotatably mounted in bearings 51 carried by the frame 10, and secured to the shaft 50, adjacent one end thereof, is a shipper fork 52 operatively connected with the wedge 44. It will be noted, in the present arrangement, that as the hand lever 45 is moved in the direction of the arrow 53, the wedge 44 will be forced inwardly between the rollers 42 in a manner to establish connection between the drum shaft 25 and driving member 30, and that when the lever is moved to its neutral position, shown in Figs. 1 and 2, the wedge 44 will be withdrawn, and the bands 40, by reason of the action of springs 54, connected to the levers 39, will be withdrawn from engagement with the drum 41, thereby permitting the gear 28 to rotate with the shaft 25 without in any way affecting any movement of the driving member or sleeve 30.

It will be observed from the foregoing description, that movement of the lever 45 in the direction indicated by the arrow 53 in Fig. 2 will establish a connection between the continuously rotating drum shaft 25 and the driving member or sleeve 30, and that through the sprocket 31, chain 36, sprocket 34, shaft 33, sprocket 35, chain 37 and sprocket 38, the shipper shaft will be rotated in a direction to reciprocate the dipper stick 21 in a manner to move the dipper 22 inwardly toward the boom 17.

Obviously, if desired, the sprockets 34 and 35 may be formed integrally and rotatably mounted on the boom pivot shaft 33, but, in the present instance, I have preferred to constitute the sprockets 34 and 35 and the shaft 33 as a power transmitting member mounted concentrically with the boom pivot for transmitting the power from the driving member 30 to the shipper shaft 18.

For reversing the movement of the shipper shaft 18 and dipper stick 21 in a manner to impart a crowding or outward movement of the

stick and dipper 22, a back shaft 55 which functions as a reversing shaft is rotatably mounted in bearings 56 suitably positioned on the swing body or frame 10 and operatively connected to the drum shaft 25 in a manner to be driven thereby through a pinion 57 secured to the shaft 55 by means of a key 58 and adapted to mesh with the gear 28 secured to the drum shaft.

Rotatably mounted on the back shaft 55 is a driving member or sleeve 59 carrying a small sprocket 60 adapted to be connected by means of a chain 61 with the relatively large removable sprocket 32 secured to the driving member or sleeve 30 rotatably mounted on the drum shaft 25.

For connecting the back shaft 55 to the driving member or sleeve 59, a ring 62 is secured by means of a key 63 to the back shaft 55, and pivotally mounted on the ring 62 are a plurality of bell crank levers 64, the short arms of which are operatively connected to segmental clutch bands 65 adapted to engage a drum 66 carried by the driving member or sleeve 59 in a manner to cause the sprocket 60 to rotate with the back shaft 55.

For operating the bell crank levers 64, a drum 67 is rotatably mounted on the hub portion of the ring 62 and integrally associated with the drum 67 are a plurality of cams 68 adapted to co-operate with anti-friction rollers mounted on the free ends of the long arms of the bell crank levers 64 in a manner to rock the bell crank levers about their pivotal connection with the ring 62, and cause the bands 65 to engage the drum 66, thereby connecting the back shaft 55 and sprocket 60.

For operating the cams 68 in a manner to establish the connection between the back shaft 55 and sprocket 60, a band 69 is secured, at one of its end portions, by means of a bolt 70, to a bracket 71 carried by an upright frame member 72, and at its opposite end portion to an arm 73 secured to a shaft 74, rotatably mounted in a bracket 75 secured to the frame member 72. The intermediate portion of the band 69 is positioned adjacent the drum 67 in a manner to retard the rotation of the drum and movement of the cams 68 carried thereby, when the band 69 is drawn into engagement with the drum 67, thus causing the anti-friction rollers on the bell crank lever 64 to move outwardly onto the high sides of the cams in a manner to cause the band 65 to engage the drum 66. Thereafter the shaft 55, ring 62 and drum 67 will rotate together against the action of the band 65, thereby retaining the cams 68 and bell crank levers 64 in clutch-band operating position, and when the band 69 is disengaged from the drum 67, the springs 68a will act to move the cams 68 forwardly to their normal position, thereby releasing the bands 65 from engagement with the drum 66.

For placing a tension on the band 69 in a manner to operate the connecting means between the back shaft 55 and sprocket 60, an arm 76 is secured to the shaft 74 and to its outer or free end is pivotally connected one end of a link 77, the opposite end of which is pivotally connected to an arm 78 secured to a shaft 79, rotatably mounted on the frame 10. Secured also to the shaft 79 is an arm 80 having its free end connected by means of a link 81 to an arm 82 secured to the shaft 46, to which the manually operated lever 45 is also secured.

It will be observed that by moving the lever 45 in the direction of the arrow 83 (Fig. 2) the shaft 74, by reason of the connections just described,

will be rocked in its bearings, thereby tensioning the band 69 and causing the intermediate portion thereof to impinge the drum 67 in a manner to retard the rotation of the drum and movement of the cams 68 for operating the bell crank levers 64 as above described.

It will be observed by reference to the drawings, particularly Figs. 1, 2, 3 and 4, that the drum shaft 25 and back shaft 55 are rotated in opposite directions and that by connecting the driving member 30 to the drum shaft 25, the shipper shaft will be rotated in one direction at substantially the speed of rotation of the drum shaft, and the stick 21 and dipper 22 moved rearwardly toward the boom, and that by connecting the sprocket 60 to the back shaft, the driving member 30 will be rotated in the opposite direction at a much reduced speed by reason of the relative sizes of the sprocket 60 and removable sprocket 32, and this reverse movement and reduced speed will be transmitted through the chain 36, sprocket 34, shaft 33, sprocket 35, chain 37 and sprocket 38 to the shipper shaft 18; thereby reversing the rotation of the shipper shaft in a manner to move the stick 21 and dipper 22 outwardly or away from the boom, and imparting to the dipper a crowding motion at a speed considerably less than that of the shovel and stick in the opposite direction.

It will be observed also from the foregoing description that movement of the lever 45 in one direction from its intermediate or normal position shown in Figs. 1 and 2 will actuate the connecting means between the drum shaft 25 and the driving member 30 in a manner to rotate the shipper shaft and move the dipper stick in one direction, and that movement of the manually operated lever in the opposite direction from its intermediate position will actuate the connecting means between the back shaft 55 and sprocket 60, in a manner to rotate the shipper shaft and move the dipper stick in the opposite direction.

For securing the member 30 against rotation in either direction when disconnected from both the shafts 25 and 55 a brake band 84 (Fig. 3) co-operable with the drum 41 may be connected in any suitable manner with the frame 10 and operated in any convenient manner, as for example, as is customary in machines of the character described, by a foot lever, or other suitable means.

For converting the power shovel shown in Fig. 1 and adapting it for use as a crane, the chain 36 may be removed and the sprocket 31 covered by a suitable drum lagging 85 (Figs. 6, 7 and 8) formed of a pair of segmental members 86 adapted to be positioned over and around the driving member 30, and secured thereon by means of bolts 87 having its opposite end portions provided with right and left hand screw threads adapted to co-operate with similarly threaded bosses 88 formed on the inner side of the respective segments 86, the middle or center portions of the bolts 87 being provided with enlarged polygonal shaped portions or shoulders 89 adapted to receive a tool for rotating the bolts in a manner to draw the segments 86 toward each other and into proper position around the driving member 30. Suitably positioned on the inner sides of the segments 86, forming the drum lagging 85, are a plurality of inwardly extending projections or lugs 90 adapted to co-operate with the interdental spaces around the toothed sprocket 31 in a manner to prevent relative rotation of the

drum lagging 85 and driving member or sleeve 30. This drum lagging 85, when the machine is adapted for use as a crane, provides means on which a cable or rope may be wound for use in the operation of the crane.

When the drum lagging 85 is mounted on the driving member, the removable sprocket 32 may be disconnected and removed from the radially disposed flange 91 formed on the member 30, and in its stead an annular guard member or ring 92 may be attached to the flange 91 to prevent the cable or the like wound on the drum lagging 85 from entering the otherwise open space between the flange 91 and the flange 93 formed on a drum 94, positioned on the shaft 25 adjacent the member 30.

Obviously, in converting the machine to use as a crane, other and suitable changes will be made, as, for example, the boom 17 will be replaced by a boom of greater length and different construction, and cables or ropes will be trained over suitable pulleys or the like for raising and lowering the boom and for hoisting material to be handled. These elements, however, have not been shown in the present instance, as they form no part of the present invention.

It will be observed from the foregoing specification that the present invention provides novel means for actuating the dipper sticks of power shovels and also provides a novel construction and arrangement for imparting an efficient crowding and retracting motion to the dipper and dipper stick, also that novel means are provided for adapting the machine for use as a crane and that machines of the character disclosed are improved in sundry details as heretofore described and particularly pointed out in the appended claims.

Obviously, the present invention is not limited to the precise construction and arrangement shown and described, as the same may be variously modified. Moreover, all the features of the invention need not be used conjointly as the same may be used to advantage in variously different combinations and sub-combinations.

What I claim as my invention and desire to secure by Letters Patent is:

1. In an excavating machine, a working platform, a boom pivoted thereon at two widely spaced points, a dipper handle slidable in the boom, a shipper shaft associated therewith to drive it, a jack shaft interposed between and concentric with the two pivot connections of the boom on the working platform, a sprocket and chain drive interposed between the shipper shaft and the jack shaft and means for driving the jack shaft.

2. In an excavating machine, a working platform, a boom pivoted thereon at two widely spaced points, a dipper handle slidable in the boom, a shipper shaft associated therewith to drive it, a jack shaft interposed between and concentric with the two pivot connections of the boom on the working platform, a sprocket and chain drive interposed between the shipper shaft and the jack shaft, said means comprising a reversing shaft, a sprocket and chain connection between it and the jack shaft and means interposed between the reversing shaft and the motor for driving it selectively in opposite directions.

3. In an excavating machine, a working platform, a boom pivoted thereon, the pivot connection between the boom and platform comprising two pairs of hingedly co-operating sep-

- 5 separate spaced brackets on boom and platform, hollow pivot trunnions one for each pair of brackets formed integrally with one of the brackets of each pair to hold the brackets on
10 boom and platform together in hinging relation, a dipper handle slidable and rotatable on the boom, a shipper shaft associated therewith, a jack shaft on the platform concentric with the pivot axis of the boom and carried by said hollow pivot trunnions and a sprocket and chain connection between the jack shaft and the shipper shaft.
- 15 4. In an excavating machine, a working platform, a boom pivoted thereon, the pivot connection between the boom and platform comprising two pairs of hingedly co-operating separate spaced brackets on boom and platform, hollow pivot trunnions one for each pair of brackets formed integrally with each of the brackets on the platform to hold the brackets on boom and platform together, a dipper handle slidable and rotatable on the boom, a shipper shaft associated therewith, a jack shaft on the platform concentric with the pivot axis of the boom and carried by said hollow pivot trunnions a sprocket and chain connection between the jack shaft and the shipper shaft, the jack shaft being mounted at its extremities in said hollow pivot
20 trunnions and extending between the two points where the boom is pivoted on the platform, and driving means for the jack shaft including a reversing shaft.
- 25

jack shaft being mounted at its extremities in the hollow pivot trunnions and extending between the two points where the boom is pivoted on the platform.

- 5 5. In an excavating machine, a working platform, a boom pivoted thereon, the pivot connection between the boom and platform comprising two pairs of hingedly co-operating separate spaced brackets on boom and platform, hollow pivot trunnions one for each pair of brackets formed integrally with each of the brackets on the platform to hold the brackets on boom and platform together, a dipper handle slidable and rotatable on the boom, a shipper shaft associated therewith, a jack shaft on the platform concentric with the pivot axis of the boom and carried by said hollow pivot trunnions a sprocket and chain connection between the jack shaft and the shipper shaft, the jack shaft being mounted at its extremities in said hollow pivot
10 trunnions and extending between the two points where the boom is pivoted on the platform, and driving means for the jack shaft including a reversing shaft.

EDMUND JOSEPH KANE. 25
